Patented Apr. 13, 1926.

UNITED STATES PATENT OFFICE.

ARNOLD BOHNENBLUST, OF RILEY, KANSAS.

ANTIFREEZING DEVICE.

Application filed May 8, 1925. Serial No. 28,988.

To all whom it may concern:

Be it known that I, ARNOLD BOHNENBLUST, a citizen of the United States, residing at Riley, in the county of Riley and State of Kansas, have invented a new and useful Antifreezing Device, of which the following is a specification.

This invention aims to provide novel means for transmitting motion from one pump rod to another, to provide novel means whereby a supply of water may be directed away from a pump, when the temperature is low enough so that water is likely to freeze up the pump, and to provide novel means 10 for housing both of the instrumentalities above mentioned.

It is within the province of the disclosure to improve generally and to enhance the utility of devices of that sort to which the 20 invention appertains.

With the above and other objects in view which will appear as the description proceeds, the invention resides in the combination and arrangement of parts and in the 25 details of construction hereinafter described and claimed, it being understood that changes in the precise embodiment of the invention herein disclosed may be made within the scope of what is claimed, without departing from the spirit of the invention. 30

In the accompanying drawings:—

Figure 1 shows in section, a device constructed in accordance with the invention, mounted in place for operation, parts appearing in elevation; Figure 2 is a horizontal section taken through the casing, on the line 2—2 of Figure 3; Figure 3 is a sectional view taken about on the line 3—3 of Figure 2; Figure 4 is a section taken about on the 40 line 4—4 of Figure 3.

In carrying out the invention, there is provided a casing 1. The casing 1 comprises a body 2. Side plates 3 are secured at 4 to the body. The side plates 3 have outwardly 45 extended bearings 5 located adjacent at one end of the body 2. There is a partition 6 in the body 2. The partition 6 forms, in the body 2, a first chamber 7, and a second chamber 8. At one end, the body 2 has a depending inlet nipple 9. The inlet nipple 9 50 communicates with the first chamber 7. At the said end of the body 2, the same is provided with an upstanding outlet nipple 10. The nipple 10 communicates with the second 55 chamber 8. The said end of the body 2 has

a lateral outlet nipple 11. The outlet nipple 11 communicates with the chamber 7.

In side elevation, the casing 1 is of approximately triangular form. Adjacent to the smaller end of the casing 1, the partition 6 is enlarged to form a tubular valve housing 12. The valve housing 12 has elongated side ports 14. The ports 14 communicate, respectively, with the chambers 7 and 8. Any kind of a valve may be used. In the drawings, there is shown a tapered rotary valve 15 which is journaled in a correspondingly shaped bore in the valve housing 12. The valve 15 has a transverse passage 16. The passage 16 is adapted to be 70 brought into and out of registration with the ports 14. The valve 15 is provided at its lower end with a reduced part 17. Nuts 18 are threaded on the part 17 of the valve. The nuts 18, cooperating with a projection 19 on the body 2, may be employed to seat the valve 15 properly in the housing 12. The valve 14 has a stem 20 at its upper end. The stem 20 extends outwardly through a cap 21 threaded on a projection 22 on the body 2. A packing 23 may be disposed about the stem 20, beneath the cap 21. At its upper end, the stem 20 has a squared extremity 24.

A shaft 25 is journaled in the bearings 5 and in the partition 6. A packing gland 26 prevents leakage through the partition 6, about the shaft 25. Arms 27 and 28 are keyed at 29 to the shaft 25. The arm 27 is located in the chamber 8, and the arm 28 90 is located in the chamber 7.

The numeral 30 designates a pit seated in the ground 31. The numeral 32 designates, diagrammatically, a trough or other container, supplied with water through a conduit 35, under the control of a cock 50. A pump 33 is mounted on the pit 30. The casing 1 is disposed in the pit 30. A pipe 34 leads from the pump 33 to the nipple 10 of the casing 1. The aforesaid conduit 35 100 leads between the nipple 11 of the casing 1 and the house 32. A well casing 36 is shown extending downwardly from the pit 30. A pipe 37 is connected to the nipple 9 of the casing 1 and extends downwardly into the casing 36. In the pipe 37, a pump 38 is disposed. The pump 38 is operated by a rod 39 located in the pipe 37. The rod 39 is pivoted at 40 to the arm 28. The rod from the pump 33 is marked by the numeral 41. 110

The rod 41 extends downwardly through the pipe 34 and is pivoted at 42 to the arm 27.

The valve 15 may be operated by a shaft 43 extended upwardly through the top of the pit 30 and provided at its lower end with a socket 44 secured by a cotter pin 45 or the like on the squared end 24 of the valve 15. The body 2 of the casing 1 is provided 10 with a detachable closure plate 46 which gives access to the packing gland 26.

When the valve 15 is in open position, the water moves upwardly through the pipe 37, and when the cock 50 is in closed position, 15 into the chamber 7, through the ports 14 of the valve housing 12 and through the passage 16 of the valve 15, into the chamber 8, and, from the chamber 8, water moves upwardly through the pipe 34 to the pump 33. 20 When the valve 15 is closed by means of the operating member 43, and when the cock 50 is opened, the water moves upwardly through the pipe 37 into the chamber 7, and passes through the conduit 35 to the place 25 32 where the water is to be used.

The operating mechanism for the pump 33 is designated by the numeral 47, but it will be understood that a windmill or any other kind of a motor may be used to operate 30 the pump. Reciprocation is imparted to the pump rod 41, the rod 41 swinging the arm 27, the arm 27 rocks the shaft 25, the shaft 25 swings the arm 28 and, by means of the rod 39, the pump 38 is operated. Owing to 35 the construction of the operating mechanism, the efficiency of the device is increased. It will be observed that the casing 1 and parts associated therewith, are housed in the pit 30 and are not likely to freeze. Since 40 the two arms 27 and 28 are provided, the disadvantages incident to a long pump rod are avoided.

I claim:—

1. In a device of the class described, a 45 casing having chambers provided with open-

ings in their outer walls, a valve controlling the passage of liquid from one of the chambers to the other, a shaft journaled in the casing, and arms carried by the shaft, one arm being located in each chamber. 50

2. A device of the class described, constructed as set forth in claim 1, and further characterized by the provision of pipes communicating with the openings, and pump connections assembled with the arms and 55 operating in certain of the pipes.

3. In a device of the class described, a casing having a partition defining chambers provided with openings in their outer walls, a valve controlling the passage of liquid 60 from one of the chambers to the other, the valve being located in the partition, means whereby an operator may actuate the valve from a point without the casing, a shaft journaled in the casing, and arms carried by 65 the shaft, one arm being located in each chamber.

4. In a device of the class described, a casing provided with a first chamber and with a second chamber, the first chamber 70 having an inlet and an outlet, and the second chamber having an outlet, a valve under the governance of an operator and controlling the flow of liquid from the first chamber to the second chamber, a first pump located below the casing and communicating with the inlet of the first chamber, means for conducting liquid from the outlet of the first chamber to a point of use, a second pump located below the casing and communicating with the inlet of the second chamber, 75 a shaft journaled in the casing, arms carried by the shaft, one arm being located in each chamber, means for connecting one arm with the first pump, and means for connecting the other arm with the second pump. 80

In testimony that I claim the foregoing as my own, I have hereto affixed my signature.

ARNOLD BOHNENBLUST.
